ALANSON P. BRUSH, OF DETROIT, MICHIGAN.

MANIFOLD FOR MULTICYLINDER INTERNAL-COMBUSTION ENGINES.

Application filed June 11, 1920. Serial No. 388,189.

The invention relates to manifolds for multi-cylinder internal combustion engines and consists in the novel construction by which a proportionate and homogeneous mixture is fed to each of the cylinders. To this end the invention consists in the construction as hereinafter set forth.

In the drawings:

Figure 1 is a front elevation partly in section of the manifold;

Figure 2 is a horizontal section on line 2—2 of Figure 1;

Figure 3 is a vertical central cross-section on line 3—3 of Figure 1.

In the operation of internal combustion engines by explosive mixtures formed of air and liquid fuel there is a tendency for the mixture formed in the carburetor to lose its homogeneity in passing through the manifold. This is particularly true where the subdivisions of the manifold are not symmetrical and also where there is a change in direction of the stream. Furthermore, where the stream is passing through straight portions of the manifold, the frictional resistance of the walls will retard the velocity of the outer portions of the stream with the result that more or less of the liquid carried in suspension will drop out and collect on the walls. Thus it is difficult to maintain just the same quantity and quality of mixture in each of the several cylinders.

With the present invention greater homogeneity of the mixture is maintained by symmetrizing the stream in advance of the first subdivision thereof and by arranging in alignment with said symmetrizing means, but out of the path of the subdivisions, a heated chamber, in which any liquid which is thrown out of the divided stream will be vaporized and returned thereto.

In detail, A is the exhaust manifold for a multi-cylinder engine, and B is the inlet manifold, both being arranged on the same side of the engine block. C is the inlet to the manifold B which, as shown, is a cross over passage in the engine block, the carburetor (not shown) being arranged on the opposite side of said block. D is a portion of the manifold B in alignment with the passage C and from which the branches E and E' extending laterally. There is also a straight passage F through this portion D which communicates with the chamber G surrounding a portion H of the exhaust conduit A. I is a member

placed at the entrance to the portion D forming a Venturi passage by which the stream of mixture passing through the cross-over C will be symmetrized. As this venturi is in direct alignment with the passage F, any liquid carried in suspension and which is thrown out of the stream at the bend by its own inertia will enter the pocket G and this being heated by the exhaust conduit, 65 will vaporize the liquid and return the vapor into the stream.

In the specific construction preferably employed the manifolds A and B are separately formed, so that the portions D and G thereof will register and securing means, such as bolts or studs J, will clamp these portions together. The branches E and E' of the manifold B extend to the inlet ports in the block from which passages extend to 75 the different cylinders.

With the construction as described there is no tendency to heat the air in the explosive mixture or that portion of the liquid fuel in the mixture which remains in suspension, but the larger masses of liquid, which would tend to collect on the walls of the conduit, are thrown through the port F into the chamber G and will be vaporized and returned. Any portion of the liquid fuel which may fall out in the cross-over 80 passage C will be again picked up and commingled with the stream by the venturi I and as this venturi symmetrizes the stream, the divided portions thereof passing through 85 the branches E and E' will be uniform in quality.

What I claim as my invention is:

1. In a multi-cylinder engine, the combination with an intake conduit having a plurality of symmetrically arranged branches, of a venturi in advance of said branches for symmetrizing the stream before sub-dividing the same, and a heated chamber communicating with said conduit in alignment with said venturi for receiving and trapping any portion of the liquid fuel thrown out of the stream by its inertia and for vaporizing and returning the same.

2. In a multi-cylinder engine, the combination with an intake conduit, an inlet portion and a plurality of symmetrically arranged laterally extending branches, an exhaust conduit adjacent to said intake conduit, and a chamber integral with said exhaust conduit and disposed beyond the junction of said intake inlet portion and its

branches, said chamber communicating with said intake in alignment with the inlet portion thereof for receiving and trapping any portion of the liquid fuel thrown out by its inertia when the direction of the stream is changed.

3. In a multi-cylinder internal combustion engine, the combination with an engine block having a cross-over passage for the intake, of an inlet manifold detachably arranged on one side of said block having a portion communicating with said cross-over, and a plurality of laterally extending branches on opposite sides thereof, an exhaust conduit on the same side of the block having a portion extending adjacent to said intake manifold, and a chamber surrounding said exhaust conduit communicating with said intake manifold in alignment with said cross-over, whereby any liquid fuel thrown out of the stream by its inertia will be received by said chamber, vaporized and returned.
4. In a multi-cylinder engine, the combination with an intake conduit having a substantially horizontal portion, a pair of

branch passageways extending laterally of said horizontal portion in opposite directions, and a heated chamber communicating in alignment with said horizontal portion and disposed on the opposite side of said branch passageway from said horizontal portion, said chamber communicating with said horizontal portion.

5. In a multi-cylinder engine, the combination with an intake conduit having a horizontal portion, a pair of branch passageways extending laterally of said horizontal portion in opposite directions forming a bend, a horizontally arranged chamber in alignment with said horizontal portion and disposed on the opposite side of said laterally extending branch passageways from said horizontal portion, the bottom of said chamber being slightly lower than said horizontal portion, and an exhaust conduit extending substantially vertically through said chamber forming an annular heated chamber surrounding the same.

In testimony whereof I affix my signature.

ALANSON P. BRUSH.
